(57) **CLAIM**

The ornamental design for a multi-compartment food container, as shown and described.

DESCRIPTION

FIG. 1 is a top perspective view of the multi-compartment food container, showing my new design;
 FIGS. 2 and 3 are front and rear elevation views, respectively, of the design illustrated in FIG. 1;
 FIGS. 4 and 5 are right and left elevation views, respectively, of the design illustrated in FIG. 1;
 FIG. 6 is a top view of the design illustrated in FIG. 1; and,
 FIG. 7 is a bottom view of the design illustrated in FIG. 1.
